OF NEW YORK, N. Y.

DESIGN FOR A TEXTILE FABRIC OR SIMILAR ARTICLE

Application filed October 22, 1932. Serial No. 45,486. Term of patent 3½ years.

To all whom it may concern:

Be it known that I, CARL R. HELLMAN, a citizen of the United States of America, residing at 150 West 82 Street, New York, New York, have invented a new, original, and ornamental Design for a Textile Fabric or Similar Article, of which the following is a specification, reference being had to the accompanying drawing, forming a part thereof.

The figure is a plan view of a textile fabric showing one fourth of my new design. The portion shown in detail is repeated through-

out and about the common center so as to complete the design, as shown in the solid portion. The wavy line represents a break line, the design being the same on both sides thereof.

I claim:

The ornamental design for a textile fabric or similar article as shown and described.

In testimony whereof I have signed this specification.

CARL R. HELLMAN.
